PIPE WRENCH

John W. Bauman and Stanley W. Bauman, Sassafrasville, Pa., and Irwin W. Bauman, Bluffton, Ohio

Application April 5, 1933, Serial No. 664,612

1 Claim. (Cl. 81—103)

The invention relates to a wrench and more especially to a quick adjustable pipe wrench.

The primary object of the invention is the provision of a wrench of this character, wherein the jaws are normally in open position to grip a pipe or other article or part to be turned and such jaws are susceptible of a wide range of adjustment so as to accommodate either large or small work and in the adjustment of the jaws the same 10 will firmly and positively grip the work.

Another object of the invention is the provision of a wrench of this character, wherein one of the jaws is pivotally supported and the other jaw slidably supported, the jaws in the assembly 15 of the wrench being assured of maximum strength and susceptible of quick adjustment.

A further object of the invention is the provision of a wrench of this character which is simple in construction, thoroughly reliable and efficient in operation, light of weight yet strong, durable, readily and easily adjusted with dispatch, and inexpensive to manufacture.

With these and other objects in view, the invention consists in the features of construction, 25 combination and arrangement of parts as will be hereinafter more fully described in detail, illustrated in the accompanying drawings, which disclose the preferred embodiment of the invention, and pointed out in the claim hereunto 30 appended.

In the accompanying drawings:

Figure 1 is a side elevation partly in section of the wrench constructed in accordance with the invention.

Figure 2 is an edge view of the same.

Figure 3 is a sectional view on the line 3—3 of Figure 1.

Figure 4 is a sectional view on the line 4—4 of Figure 1 looking in the direction of the arrows.

Figure 5 is a perspective view of the latching member for holding the sliding jaw in adjusted position when gripping work.

Figure 6 is a view similar to Figure 1 showing a slight modification.

Figure 7 is a sectional view on the line 7—7 of Figure 6.

Figure 8 is a view similar to Figure 6 showing a further modification.

Figure 9 is a sectional view on the line 9—9 of Figure 8 looking in the direction of the arrows.

Figure 10 is a perspective view of a further modified form of latching member.

Similar reference characters indicate corresponding parts throughout the several views in 55 the drawings.

Referring to the drawings in detail, particularly Figures 1 to 5 inclusive, the wrench in its preferred form includes a lever 10 constituting the handle of said wrench which is fitted in a frame 11 constituting the main body of the wrench. 5 This lever 10 is swingingly connected to the frame 11 by a pivot 12 and is limited in its swinging movement through the medium of a strap formation 13 in the frame.

The frame 11 is provided with a guideway 14 10 for the shank 15 of a sliding jaw 16, while carried by the end of the lever 10 opposite the jaw 16 is a removable jaw 17 supported upon a detachable pin 18 mounted in the lever 10. This jaw 17 preferably straddles the end of the lever 16 carrying 15 said jaw and in this manner greater strength is had in the working of the jaw.

Suitably seated in the frame 11 and imposed upon the end of the lever 10 carrying the jaw 17 is a coiled expansion spring 19 which urges the 20 lever in a position to have the jaw 17 disposed relative to the jaw 16 in an opening position. In other words, the wrench normally is open to receive the work between the jaws 16 and 17, these 25 jaws at their gripping faces being serrated or roughened as at 20 to assure a firm and positive grip upon a piece of work.

The shank 15 which travels in the guideway 14 in the frame 11 at its heel edge is formed with 30 ratchet teeth 21 and engageable with these teeth is a latching member 22 pivotally connected with a trigger 23 having the finger engaging end 24 and pivoted at 25 in the frame 11. This trigger 23 is acted upon by a leaf spring 26 which normally holds the member 22 in latching position 35 but susceptible of ratchet action with the teeth 21 in one direction. It can be seen that this sliding jaw 16 is susceptible of a wide range of sliding adjustment. The pivotal mounting of the jaw 17 permits the same to automatically or itself 40 become accommodated to the work when gripped by both jaws of the wrench.

The frame 11 in each opposite side cheek thereof is provided with a notch 27, while mounted in the shank 15 of the sliding jaw 16 is a cross pin 28 45 accommodated within the notch when the said jaw has been extended or is at the maximum extent of the range of adjustment thereof and thus such shank will be prevented from being pulled out of the guideway 14 in the frame 11.

In Figures 6 and 7 of the drawings there is shown a slight modification of wrench, wherein the ratchet acting latch member 29 is pivoted at 30 to a finger operated piece 31 pivoted at 32 in the frame 33 of the wrench and this finger piece 50 55

31 extends a distance of the lever 34 of said wrench in convenient reach for finger actuation and at the edge of said lever next to the shank of the sliding jaw of the wrench. The finger piece 5 31 has acting thereon a leaf spring 35 which serves to urge the member 29 in latching position with the shank of the sliding jaw of the wrench.

In Figures 8 and 9 of the drawings there is 10 shown a further modification of the invention, wherein the frame 36 at one side thereof is formed with an enlargement 37 in which is pivoted at 38 the trigger 39 having pivoted thereto as at 40 the ratchet acting latching member 41, while the shank 42 of the sliding jaw 43 at one side thereof is formed with the ratchet teeth 44 with which 15 engages the member 41. It will be apparent that the trigger 39 is disposed at one side of the wrench in this further modified form, while in the preferred form the trigger 23 is at the back of the wrench and in Figure 6 the finger piece 31 is 20 between the lever and the shank of the sliding jaw of the wrench.

In the preferred and modified forms of the 25 wrench as disclosed in Figures 1, 6 and 9 of the drawings it will be noted that the frame or body has provided therein thrust bearings 45, 46 and 47 respectively, which are integral with said frame to take the strain of the latching member 30 and also the jaw 17 so as to relieve the strain from the pivot of the operating lever for said latching member as well as the same and the pin connecting the jaw 17. In other words, the frame 35 constituting the body of the wrench affords a way for the latching member and this way at opposite extremities of such member constitutes a

fixed rigid bearing for the latching member to assure maximum strength thereto for the gripping of the shank of the sliding jaw and more especially when the wrench is active with a piece of work.

In Figure 10 of the drawings there is shown a slight modification of a latching member 48 wherein the link 49 therefore has one end engaged in a pocket 50 and attached to the member through a pin 51, this link 49 being operable from a trigger as hereinbefore described. 1

What is claimed is:

A wrench of the character described comprising outer and inner jaws, a sliding shank formed with said outer jaw, a frame fitted with said shank, a lever pivoted in the frame and carrying 1 said inner jaw for arcuate movement of the latter toward and away from the outer jaw, a spring fitted in said frame and working against said lever to hold the inner jaw normally outwardly inclined relative to the outer jaw, said frame having 2 a biased guideway to provide at opposite ends thereof diagonally disposed thrust bearings, and a hand released ratchet member fitted in said guideway and having opposite ends contacting with the thrust bearings, the ratchet member 25 and shank being formed with interlocking teeth having abrupt and inclined faces and the guideway being at an inclination to form with the shank an acute angle whose apex is directed toward the outer jaw, the abrupt faces of the teeth 30 on the ratchet member and shank engaging on outward movement of the shank. 35
